UNITED STATES PATENT OFFICE

2,660,838

CAM GRINDING MACHINE

Clarence J. Green, Worcester, Mass., assignor to
 Norton Company, Worcester, Mass., a corporation of Massachusetts

Application November 17, 1950, Serial No. 196,263

13 Claims. (Cl. 51—101)

1

The invention relates to grinding machines, and more particularly to an automatic cam grinding machine for grinding a plurality of spaced integral cams on a camshaft to predetermined contours and tapers.

One object of the invention is to provide a simple and thoroughly practical automatic cam grinding machine to grind a plurality of cams which taper in opposite directions. Another object of the invention is to provide a grinding machine having a rotatable work support on a longitudinally movable swivel table with an automatically actuated mechanism for swivelling the table in opposite directions to facilitate grinding opposite tapers on spaced portions of a workpiece. Another object is to provide a cam grinding machine having a longitudinally movable swivel table with a swivelling mechanism which is actuated automatically by and in timed relation with the longitudinal movement of the table successively to swivel the swivel table in opposite directions to grind oppositely tapering surfaces on certain of the cams being ground.

A further object of the invention is to provide a suitable wheel feeding mechanism having a table actuated stop mechanism for limiting the infeeding movement of the grinding wheel to compensate for the swivelling movement of the table. Another object of the invention is to provide a master cam assembly with stepped master cams which are arranged to compensate for the swivelling of the swivel in grinding oppositely tapering surfaces on spaced cams on a camshaft.

The invention accordingly consists in the features of construction, combinations of elements, and arrangements of parts as will be exemplified in the structure to be hereinafter described and the scope of the application of which will be indicated in the following claims.

In the accompanying drawings in which is shown one of various possible embodiments of the mechanical features of the invention,

Fig. 1 is a front elevation of a grinding machine embodying the invention;

Fig. 2 is a plan view of the grinding machine;

Fig. 3 is a cross-sectional view, on an enlarged scale, through the wheel slide showing the wheel feeding and wheel positioning mechanisms;

Fig. 4 is a vertical sectional view, taken approximately on the line 4—4 of Fig. 3, through the wheel slide and wheel slide base;

Fig. 5 is a fragmentary sectional view, on an enlarged scale, taken approximately on the line 5—5 of Fig. 4, showing the fluid motor for rapidly positioning the wheel slide;

2

Fig. 6 is a fragmentary vertical sectional view, on an enlarged scale, taken approximately on the line 6—6 of Fig. 3, showing the star wheel and dog indexing mechanism;

Fig. 7 is a fragmentary plan view, on an enlarged scale, of the hydraulically operated mechanism for swivelling the worktable;

Fig. 8 is a fragmentary front elevation, taken approximately on the line 8—8 of Fig. 7;

Fig. 9 is a fragmentary sectional detail view, on an enlarged scale, taken approximately on the line 9—9 of Fig. 7;

Fig. 10 is a fragmentary sectional detail view, on an enlarged scale, taken approximately on the line 10—10 of Fig. 7;

Fig. 11 is a fragmentary detail view, on an enlarged scale, taken approximately on the line 11—11 of Fig. 7;

Fig. 12 is a fragmentary rear elevation, on an enlarged scale, of the rotary feed stop disc for positioning the wheel slide;

Fig. 13 is a fragmentary plan view, on an enlarged scale, of the wheel spindle reciprocating mechanism;

Fig. 14 is a diagrammatic view showing the worktable swivelled in a counter-clockwise direction for grinding cams 1, 2, 5 and 6 with faces tapering toward the right;

Fig. 15 is a similar diagrammatic view showing the worktable swivelled in a clockwise direction for grinding cams 3, 4, 7 and 8 with faces tapering toward the left;

Fig. 16 is a combined hydraulic and electrical diagram of the operating mechanisms and the controls therefor;

Fig. 17 is a hydraulic diagram of the wheel feeding mechanism;

Fig. 18 is a diagrammatic view of a modified construction, showing the swivel table swivelled in a counter-clockwise direction in which stepped master cams are utilized; and

Fig. 19 is a similar diagrammatic view showing the swivel table swivelled in a clockwise direction.

An automatic cam grinding machine has been illustrated in the drawings comprising a base 10 which supports a longitudinally movable worktable 11 on the usual flatway 12 and V-way 13 formed on the upper surface of the base 10. The longitudinally movable table 11 supports a swivel table 14 which is arranged to pivot on a stud 15.

The base 10 also supports a transversely movable wheel slide 16 which is arranged to slide transversely on a V-way 17 and a flatway 18 formed on the upper surface of a transversely movable wheel slide base 19. The wheel slide base

55

19 is in turn supported on a V-way 20 and a flat-way 21 formed on the upper surface of the base 10. The wheel slide 16 is provided with a rotatable wheel spindle 22 journalled in bearings (not shown). The wheel spindle 22 supports a rotatable grinding wheel 23. A suitable driving mechanism is provided for driving the wheel spindle 22 and the grinding wheel 23 comprising an electric motor 24 adjustably mounted on the upper surface of the wheel slide 16. The motor 24 is connected by a V-belt drive (not shown) contained within a belt guard 25 (Figs. 1 and 2).

The swivel table 14 serves as a support for a pivotally mounted rock bar 30 which is pivotally supported by a plurality of spaced bearing brackets 31 and 32 which are in turn fixedly mounted on the upper surface of the swivel table 14. The rock bar 30 serves as a support for a master cam spindle 33 which extends within a headstock housing 29. The master cam spindle 33 is provided with a camshaft supporting center 34 for supporting the left-hand end of a camshaft 35 to be ground. The rock bar 30 also supports a footstock 36 having a footstock center 37 for supporting the right-hand end of the camshaft 35.

The master cam spindle 33 may be driven by an electric motor 38 (Figs. 1 and 2) mounted on the upper surface of the headstock housing 29. The motor 38 is drivingly connected in a manner (not shown) positively to rotate the master cam spindle 33 and the camshaft 35 to be ground. The master cam spindle 33 is provided with a plurality of master cams 39 which are arranged to be successively engaged by a master cam follower roller 40, which is slidably supported on a rotatable shaft 41, for controlling the rocking movement of the rock bar 30 so as to generate predetermined contours on the cams being ground. This mechanism is not considered to be a part of the present invention and therefore has not been illustrated in detail. The drive for the master cam spindle 33 and the arrangement of the master cams 39 and the follower roller 40 may be substantially the same as that shown in the prior U. S. Patent No. 2,185,837, to G. Crompton, Jr., dated January 2, 1940, to which references may be had for details of disclosure not contained herein.

A suitable mechanism is provided for rapidly moving the wheel slide 16 relative to the wheel slide base 19 to cause a rapid approaching movement of the grinding wheel 23 to and from an operative position relative to the camshaft 35 to be ground. This mechanism may comprise a fluid pressure cylinder 45 which is fixedly mounted on the wheel slide base 19. The cylinder 45 contains a slidably mounted piston 46 which is connected to one end of a piston rod 47. The other end of the piston rod 47 is connected to a depending bracket 48 which is fixedly mounted on the underside of the wheel slide 16.

Due to the swivelling of the swivel table 14 for grinding tapered cams, to be hereinafter described, a suitable stop mechanism is provided to limit the forward approaching movement of the wheel slide 16. This mechanism may comprise a rotatable shaft 50 (Fig. 3) which is journalled in a pair of spaced bearings 51 and 52 in the wheel slide base 19. A plate 53 is fixedly keyed on the right-hand end of the shaft 50. The plate 53 is provided with a plurality of spaced adjustable stop studs 54 which are arranged to be indexed into an operative position in the path of a bracket 55 which is fastened to the right-hand

end of the wheel slide 16 (Fig. 3). A shaft 56 is journalled in a bearing 57 which is fixedly mounted within the wheel slide base 19. The shaft 56 is slidably keyed within a central aperture formed within the left-hand end of the shaft 50. A gear 58 is mounted on the left-hand end of the shaft 56 and meshes with a gear 59 mounted on a rotatable shaft 60. The shaft 60 is journalled in a bearing 61 which is fixedly mounted relative to the base 10. The shaft 60 is also provided with a star wheel 62 (Figs. 3 and 6) which is arranged in the path of a plurality of adjustably spaced dogs 63. The dogs 63 are adjustably mounted on the rear surface of the worktable 11. A T-slot 64 is formed in the rear edge of the table 11 to facilitate supporting and adjusting the dogs 63. The mechanism just described is provided to regulate the extent of a rapid approaching movement of the wheel slide 16 when the swivel table 14 is swivelled for taper cam grinding. The stops 54 are numbered 1 to 8 inclusive to correspond with the cams 1 to 8 on the camshaft 35.

In order to obtain a predetermined controlled feeding movement of the grinding wheel 23, a suitable feeding mechanism is provided comprising a rotatable feed screw 70 which is journalled in bearings 71 and 72 fixedly mounted relative to the base 10. A depending half-nut 73 depends from the under side of the wheel slide base 19 and meshes with or engages the feed screw 70. A suitable mechanism is provided comprising manually operable feed wheel 79 for manually rotating the feed screw 70. The feed wheel 79 is mounted on the front of the machine base. A micrometer feed adjusting mechanism 80 is provided of the well known type, such as for example that shown in the expired U. S. patent to C. H. Norton, No. 762,838, dated June 14, 1904, to which reference may be had for details of disclosure not contained herein. This micrometer feed adjusting mechanism 80 serves to facilitate precisely adjusting a stop abutment not shown relative to a pivotally mounted stop pawl 81 which is pivotally supported on the front of the machine base 10.

A suitable power operated mechanism is provided for automatically rotating the feed screw 70 to impart a feeding movement to the grinding wheel 23. This mechanism may comprise a hydraulic cylinder 76 (Fig. 17) which contains a slidably mounted piston 77. A rack bar 78 is formed on the upper surface of the piston 77 and meshes with a gear 75 mounted on the end of the shaft 74. The gear 75 meshes with a gear (not shown) mounted on the forward end of a shaft 74a (Fig. 3). This feeding mechanism is substantially identical with that shown in the prior United States Patent No. 2,522,485 to Herbert A. Silven et al., dated September 12, 1950, to which reference may be had for details of disclosure not contained herein. It will be readily apparent from the foregoing disclosure that movement of the piston 77 caused by fluid admitted to the cylinder 76 will impart a rotary motion to the gear 75 and through the shaft 74 will transmit a corresponding rotary motion to the shaft 74a and the feed screw 70.

In order to operate the machine automatically the table 11 is preferably moved longitudinally by a hydraulic mechanism comprising a cylinder 85 which contains a slidably mounted piston 86. The piston 86 is connected to the left-hand end of a piston rod 87 (Fig. 16). The right-hand end of the piston rod 87 is connected by a bracket 88 which is fixedly mounted on the under side of

the table 11. It will be readily apparent that when fluid under pressure is passed through a pipe 89 into a cylinder chamber 90, the piston 86 together with the table 11 will be moved toward the right. During this movement, fluid within a cylinder chamber 91 may exhaust through a pipe 92. Similarly when fluid under pressure is admitted through the pipe 92 into the cylinder chamber 91, the piston 86 together with the table 11 will be moved toward the left.

An automatic control mechanism may be provided for controlling the admission of fluid to the cylinder 85 for automatically indexing the table 11 successively to position cams on the camshaft 35 to be ground into operative relation with the grinding wheel 23. This mechanism is not considered to be a part of the present invention and consequently has not been illustrated in detail. This mechanism may be substantially identical with that shown in the prior U. S. Patent No. 2,185,837, above referred to, to which reference may be had for details of disclosure not contained herein.

In modern practice in grinding camshafts for the automotive industry, it is desirable to grind cams not only having a predetermined contour but also tapering from side to side so that when installed in an automotive engine, the rotation of the cam on the valve tappet will cause a rotary motion to be imparted to the tappet. In some automotive engine designs it is necessary due to arrangement of the valves and tappets to provide cams having peripheral surfaces tapering in opposite directions. In some cases it is desirable to provide a taper toward the left on all cams on the left-hand end of the camshaft 35 and to provide a taper toward the right on the remainder of the cams on the right-hand end of the camshaft 35. As illustrated in the drawings the machine is set up for grinding alternate pairs of cams tapering in the opposite direction. In order to accomplish this desired result, a hydraulically operated mechanism is provided for swivelling the swivel table 14 about its pivot stud in a clockwise direction or counterclockwise direction so as to produce the desired taper on the cams being ground. This mechanism may comprise a hydraulic cylinder 98 which is fixedly mounted on the longitudinally movable table 11. The cylinder 98 contains a slidably mounted piston 99 which is connected to one end of a piston rod 100. The other end of the piston rod 100 is reduced slightly in diameter and passes through an elongated hole 101 formed in a block 102 (Fig. 10). The block 102 is pivotally supported on a stud 103 which is fixedly mounted on a bracket 104 fastened to the left-hand end of the table 11 (Figs. 7 and 9). The piston rod 100 passes through a clearance hole 105 in the stud 103. The elongated hole 101 and the clearance hole 105 are provided to facilitate a free swivelling movement of the table 14 when fluid under pressure is admitted to the cylinder 98.

When fluid under pressure is passed through a pipe 106 into a cylinder chamber 107 (Fig. 7) the piston 99 is moved downwardly to impart a counter-clockwise swivelling movement to the swivel table 14. During this movement fluid within a cylinder chamber 108 may exhaust through a pipe 109. A pair of throttle valves 110 and 111 are provided respectively in the pipes 106 and 109 to facilitate controlling the speed of movement of the piston 99 and the swivelling movement of the swivel table 14. Similarly when fluid under pressure is passed through the pipe

109 into the cylinder chamber 108, the piston 99 will be moved upwardly (Fig. 7) thereby swivelling the swivel table 14 in a clockwise direction.

It is desirable to provide precise means for limiting the swivelling movement of the swivel table 14 in either direction to facilitate grinding predetermined tapers in opposite directions on the cams being ground. The worktable 11 is provided with a pair of spaced upwardly projecting lugs 115 and 116. The lugs 115 and 116 are provided with adjustable stop screws 117 and 118 respectively which are arranged in the path of a stop lug 119 which is fastened to the left-hand end of the swivel table 14. By manipulation of the stop screws 117 and 118, the clockwise and counter-clockwise swivelling of the swivel table 14 may be precisely controlled.

The actual taper produced on the cams being ground is very slight for example a small fraction of one degree. This taper has been somewhat exaggerated in the drawings (Figs. 14 and 15) to clarify the illustration. As shown in Fig. 14, the swivel table 14 is swivelled in a counter-clockwise direction to illustrate diagrammatically the relative position of the camshaft 35 and the grinding wheel 23 while grinding cams 1, 2, 5 and 6. Similarly in Fig. 15, the swivel table has been swivelled in a clockwise direction to show diagrammatically the relative position of the camshaft 35 and the grinding wheel 23 while grinding cams 3, 4, 7 and 8 on the camshaft 35. It will be readily apparent from the foregoing disclosure that cams 1 and 2 are ground while the swivel table 14 is swivelled in a counter-clockwise direction after which the table is swivelled in a clockwise direction for grinding cams 3 and 4. The swivel table 14 is again swivelled in a counter-clockwise direction to position the camshaft 35 for grinding cams 5 and 6 after which the swivel table is again swivelled in a clockwise direction to position the camshaft 35 for grinding cams 7 and 8 so that alternate pairs of cams will be ground tapering in opposite directions.

It is desirable to provide a wheel spindle reciprocating mechanism for reciprocating the grinding wheel spindle 22 axially within its bearings during a grinding operation. This mechanism may comprise a worm 125 (Fig. 13) mounted on the wheel spindle 22. The worm 125 meshes with a worm gear 126 mounted on a vertical shaft 127. The vertical shaft 127 is provided at its upper end with an eccentric stud 128 which supports an eccentric disc 129. The eccentric disc 129 is surrounded by one part of a connecting rod 130. The connecting rod 130 is provided with a yoked end 131 which engages a stud 132 carried by a pivotally mounted yoked member 133. The yoked member 133 is pivotally supported on a stud 134 which is fixed relative to the wheel slide 16. A tension spring 135 is connected between a stud 136 on the yoked member 133 and a stud 137 fixedly mounted within the wheel slide 16. The spring 135 serves normally to maintain the stud 132 positioned within the yoke 131. The yoked member 133 is provided with opposed studs (not shown) which engage a groove (not shown) formed on the wheel spindle 22. It will be readily apparent from the foregoing disclosure that rotation of the wheel spindle 22 will be imparted through the worm 125, the worm gear 126, the shaft 127, the eccentric stud 128, the eccentric disc 129 to oscillate the connecting rod 130 which serves to impart an oscillating movement to the yoked member 133 thereby reciprocating the wheel spin-

idle 22 axially within its bearings. A pipe 155 connects the control valve 160 with a cylinder 156. The cylinder 156 contains a slidably mounted piston 157 which is arranged automatically to stop and to start wheel spindle reciprocation before and after a grinding wheel truing operation. A pipe 158 connects the control valve 160 with other mechanisms of the machine (not shown).

The mechanism as above described includes a stop plate 53 having a plurality of stop pins or studs 54 for limiting the approaching movement of the grinding wheel 23 so as to compensate for the swivelling movement of the swivel table 14. This compensation may also be obtained as illustrated diagrammatically in the modification shown in Figs. 18 and 19. In the latter figures, the diameter of the master cams 39 may be stepped or graduated, that is, of different diameters to compensate for the swivelling of the swivel table 14 so that the cams on the camshaft 35 to be ground will be ground to the same diameter. In utilizing this modified construction as diagrammatically illustrated in Figs. 18 and 19, the wheel slide 16 is fed into a predetermined forward approaching position before the wheel 23 is moved into operative engagement to grind each successive cam on the camshaft 35.

The grinding wheel 23 is formed with a true cylindrical operative face. The wheel may be maintained in true cylindrical form by means of a suitable truing apparatus such as for example, a wheel guard truing mechanism mounted on top of the wheel guard or the wheel slide or a truing tool adjustably fixed on the longitudinally movable worktable 11, in which case the truing tool is traversed in a direction parallel to the grinding wheel axis. With such an arrangement the grinding wheel may be readily trued regardless of the position of the swivel table. If desired a table type truing apparatus may be provided such as a truing tool 140 which is mounted on the rock bar 30. This truing apparatus may be substantially the same as that shown in the prior U. S. patent to Crompton above referred to. In utilizing this type of truing mechanism, the swivel table must be swivelled to a central position for the truing operation. In order to locate the swivel table 14 in position for truing, a hydraulically operated mechanism may be provided comprising a cylinder 145 (Fig. 7) which contains a slidably mounted piston 146. The piston 146 is provided with an integral piston rod 147 which carries a stop block 148. The stop block 148 is arranged so that it may be moved into the path of the lug 116 on the table 11 and a stop screw 149 carried by the lug 119 on the end of the swivel table. When fluid under pressure is passed through a pipe 150 into a cylinder chamber 151, the piston 146 is moved toward the right (Fig. 7) to move the stop block 148 into an operative position. During this movement, fluid within a cylinder chamber 152 may exhaust through a pipe 153 and through a valve 154. The valve 154 is provided in case it is desired to render the cylinder 145 and the piston 146 inoperative. In the latter case when the piston 146 is in a left-hand end position (Fig. 7), the cylinder chamber 152 is filled with fluid, the valve 154 may be closed thereby locking the fluid within the cylinder chamber 152 and holding the piston 146 and the stop block 148 in an inoperative or left-hand end position. The operation of the cylinder 145 is automatic

and ties in with the automatic control system to be hereinafter described.

A suitable hydraulic control mechanism is provided for controlling the admission to and exhaust of fluid from the cylinders 98 and 145. This control mechanism may comprise a solenoid actuated valve 160 which is actuated by means of a solenoid S1, a control valve 161 which is actuated by a solenoid S4 and a control valve 162 which is actuated by the solenoids S2 and S3. The control valve 160 serves to control the admission of fluid to the cylinder chamber 151 in the cylinder 145 for moving the stop block 148 into an operative position. The control valve 162 serves in one position to admit fluid under pressure to the control valve 161 and in the other position to admit fluid through the pipe 109 into the cylinder chamber 108 to move the piston 99 upwardly (Figs. 7 and 16) to swivel the swivel table 14 in a clockwise direction. The control valve 161, in the position illustrated in Fig. 16, serves to pass fluid under pressure through the pipe 106 into the cylinder chamber 107 to move the piston 99 downwardly thereby rocking the swivel table 14 in a counter-clockwise direction into the position illustrated in Fig. 16. In the reverse position of the valve 161, fluid is passed through the pipe 153 into the cylinder chamber 152 to move the piston 146 toward the left (Figs. 7 and 16) to withdraw the stop block 148 to an inoperative position. As above explained if desired the stop block 148 may be locked in an inoperative position by closing the valve 154 when the piston 146 is in a left-hand end position (Figs. 7 and 16).

As shown in Fig. 16 the machine is set up for grinding alternate adjacent pairs of cams on the camshaft 35 tapering in the opposite directions as shown in Figs. 14 and 15. A pipe 164 serves to supply fluid under pressure to the solenoid actuated valve 160. The valve 160 comprises a slidably mounted valve member 163 which is normally held in a right-hand end position by means of a compression spring 166. When the solenoid S1 is energized, the valve member 163 is shifted toward the left. When the solenoid S1 is energized, fluid under pressure from the pipe 164 may pass through a valve chamber 165, through the pipe 150 into the cylinder chamber 151 to move the piston 146 toward the right into the position illustrated in Fig. 7 thus moving the stop block 148 into an operative position.

The fluid actuated control valve 161 is a pressure actuated valve comprising a slidably mounted valve member 168 the movement of which is controlled by a pilot valve 169. The pilot valve 169 comprises a slidably mounted valve member 170 which is normally held in a right-hand end position by means of a compression spring 171. The solenoid S4 when energized serves to shift the valve member 168 into a right-hand end position. In the position as illustrated in Fig. 16, fluid under pressure passing through the pipe 164 passes through a passage 173 into an end chamber 174 to move the valve member 168 into an extreme left-hand end position as shown in Fig. 16. During this movement fluid within an end chamber 175 may exhaust through a passage 176, through a central passage 177 in the pilot valve member 170 and exhaust through a pipe 178.

In the position of the valve member 168 (Fig. 16) fluid under pressure passing through the pipe 186 passes through a valve chamber 181

and through the pipe 106 into the cylinder chamber 107 to cause a downward movement of the piston 99, thereby rocking the swivel table in a counter-clockwise direction into the position illustrated in Fig. 16. When the valve member 168 is shifted into a reverse position, that is, its extreme righthand end position, fluid under pressure passing through the pipe 186 passes through the valve chamber 187 and through the pipe 153 into the cylinder chamber 152 to move the piston 146 toward the left (Figs. 7 and 16) thereby moving the stop block 148 to an inoperative position.

The control valve 162 comprises a slidably mounted valve member 180 which is controlled by a slidably mounted pilot valve member 181. The pilot valve member is shown in an extreme left-hand end position and is arranged to be actuated by means of the solenoids S3 and S2. In the position of the valve 162 (Fig. 16) fluid under pressure from the pipe 164 passes through a chamber in the pilot valve member 181, through a passage 182 into an end chamber 183 to move the valve member 180 into a right-hand end position as illustrated in Fig. 16. During this movement of the valve member 180 fluid within an end chamber 184 may exhaust through a passage 185 and out through an exhaust pipe 178. When the valve member 180 is in a right-hand end position fluid under pressure in the pipe 164 passes through a valve chamber 186a and through the pipe 186 to admit fluid to the valve chamber 187 in the central valve 161.

When the solenoid S2 is energized, the pilot valve member 181 is shifted toward the right so that fluid under pressure from the pipe 164 passes through the passage 185 to shift the valve member 180 toward the left so that fluid under pressure from the pipe 164 passes through the valve chamber 186a and through the pipe 109 into the cylinder chamber 108 to cause an upward movement of the piston 99 thereby imparting a clockwise swivelling movement to the swivel table 14.

To facilitate automatically controlling the valves 160, 161 and 162, a plurality of limit switches actuated by adjustable dogs on the front edge of the table are provided. An adjustable table dog 190 is provided for actuating a vertically movable plunger 191 against the compression of a spring 192. A downward movement of the plunger 191 caused by dog 190 serves to close the normally open limit switches LS9 and LS10. A normally open limit switch 195 is arranged to be actuated by a pair of adjustable dogs 196 and 197 when the table is moved toward the right. A normally open limit switch 198 is arranged to be closed by an adjustable dog 199 when the table 11 is moved toward the right. Similarly a normally open limit switch 200 is arranged to be actuated by an adjustable table dog 201 when the table 11 is moved toward the right. In the operation of the arrangement shown in Fig. 16, the swivel table 14 is swivelled after each pair of cams have been ground so that surfaces tapering in the opposite direction are produced on adjacent pairs of cams. The table dogs 196, 197, 199 and 201 are arranged so that during the movement of the table 11 toward the left, the dogs ride idly over the respective limit switches. As shown in Fig. 16, the table is shown in a start position, that is, with the table in a left-hand end position. When a grinding cycle is started, the table 11 indexes toward the right to position cam No. 1 on the camshaft 35 in an operative position rel-

ative to the grinding wheel 23. After the first two cams on the right-hand end of the cam-shaft have been ground and the table starts the next indexing movement toward the right, the dog 197 engages and closes the limit switch 195 to energize the solenoid S2 thereby shifting the pilot valve member 181 toward the right so that fluid under pressure from the pipe 164 passes through the passage 185 into the end chamber 184 to shift the valve member 180 toward the left. In this position of the valve member 180, fluid under pressure passing through the pipe 164 passes through the valve chamber 186a and through the pipe 109 into the cylinder chamber 108 to move the piston 99 upwardly (Fig. 16) to swing the swivel table 14 in a clockwise direction to position the camshaft 35 for grinding cams No. 3 and No. 4 so that the surfaces will taper toward the left. After the third and fourth cams have been ground and the table starts its indexing movement toward the right, the dog 199 engages and closes the limit switch 198 which serves to energize the solenoid S3 to shift the pilot valve member 181 toward the left into the position illustrated in Fig. 16. In this position of the pilot valve member 181, fluid under pressure from the pipe 164 passes through the passage 182 into the end chamber 183 to shift the valve member 180 toward the right so that fluid under pressure passing through the pipe 164 may pass through the pipe 186 into the valve chamber 187 of the valve 161 and through the pipe 106 into the cylinder chamber 109 to cause a downward movement of the piston 99 (Fig. 16) to again swivel the swivel table 14 in a counter-clockwise direction to position the camshaft 35 for grinding cams No. 5 and No. 6 on the camshaft 35 with surfaces tapering toward the right.

During the next indexing movement of the table toward the right, the dog 196 engages and closes the limit switch 195 so as to again energize the solenoid S2 thereby shifting the valve member 180 toward the left and in a manner above described causing fluid under pressure to pass into the cylinder chamber 108 to cause an upward movement of the piston 99 thereby swivelling the swivel table 14 in a clockwise direction to position the camshaft 35 in position for grinding cams No. 7 and No. 8 on the cam-shaft 35 with surfaces tapering toward the left.

After the cam No. 8 has been ground, the table moves through an idle stroke toward the left. As the grinding wheel 23 approaches the truing tool 140, the dog 190 engages and depresses the plunger 191 to close the limit switches LS9 and LS10. The closing of the limit switch LS9 serves to energize the solenoid S1 to shift the valve member 163 so that fluid under pressure from the pipe 164 passes through a chamber in the valve member 163, through the pipe 150 into the cylinder chamber 151 to cause the piston 146 to move toward the right (Figs. 7 and 16) to position the stop block 148 in an operative position between the lug 116 and stop screw 149. At the same time the closing of the limit switch LS10 energizes the solenoid S3 to shift the valve member 180 into a right-hand end position (Fig. 16) so that fluid under pressure will be passed through the pipe 186 into the valve chamber 187 of the valve 161 and through the pipe 106 into the cylinder chamber 107 to cause a downward movement of the piston 99 to swivel the swivel table 14 in a counter-clockwise direction. The swivelling movement of the table in a counter-clockwise direction continues until the stop screw

149 engages the stop block 148 thereby locating the swivel table in a central position for a grinding wheel truing operation. Continued movement of the table 11 toward the left passes the truing tool 140 across the face of the grinding wheel. During this movement, the dog 201 rides idly over the limit switch 200. After the truing tool has completed one pass across the grinding wheel 23, the table 11 is automatically reversed and starts its movement in the reverse direction to again traverse the truing tool 140 across the operative face of the grinding wheel. After the second pass of the truing tool 140 across the face of the wheel 23, the dog 201 momentarily closes the limit switch 200 to momentarily energize the solenoid S4 which shifts the pilot valve 170 toward the left (Fig. 16) to pass fluid through the passage 176 into the end chamber 175 to shift the valve member 168 toward the right so that fluid under pressure passing through the pipe 186 passes through the valve chamber 187 and through the pipe 153 into the cylinder chamber 152 to move the piston 146 toward the left thereby withdrawing the stop block 148 to an inoperative position.

The valve member 168 remains in the right-hand end position only momentarily. As soon as the solenoid S4 is deenergized, the released compression of the spring 171 shifts the valve member 170 into the position illustrated in Fig. 16 to shift the valve member 168 into its left-hand end position (Fig. 16) so that fluid under pressure in the pipe 186 passes through the chamber 187, through the pipe 106 into the cylinder chamber 107 to continue the downward movement of the piston 99 thereby completing the swivelling movement of the swivel table 14 in a counter-clockwise direction so that the swivel table 14 is positioned correctly for grinding cams Nos. 1 and 2 on the next camshaft 35. The traversing movement of the table 11 stops at the end of the cycle in the position as illustrated in Fig. 16. The ground camshaft 35 may then be removed from the machine and a new cam-shaft inserted therein after which the cycle of operation can again be carried out in a manner above described.

The operation of the positioning and feeding movements is coordinated as follows: fluid under pressure is passed through a pipe 205, through a throttle valve 206, into a cylinder chamber 207 to cause the piston 46 to move toward the left (Figs. 5 and 17) to cause a rapid approaching movement of the slide 16. During the rapid approaching movement of the slide, fluid within a cylinder chamber 208 may exhaust through a pipe 209, through a control valve 210 and exhaust through a pipe 211. At the same time fluid under pressure passes through the pipe 205, it passes also through a throttle valve 212 into a cylinder chamber 213 to cause the piston 77 to move toward the right thereby imparting a rotary motion through the gear 74 to rotate the feed screw 70 to impart a feeding movement to the wheel slide base 19 and the grinding wheel slide 16. This latter feeding movement serves as a grinding feed to advance the grinding wheel 23 into the cam being ground during the grinding operation. During the infeeding movement caused by the piston 77, fluid within a cylinder chamber 214 may exhaust through a pipe 215, through a throttle valve 216 and out through the exhaust pipe 211 into the reservoir. At the end of a grinding operation on a cam being ground, fluid is passed through the pipe 211 and through a check valve 217 into the cylinder 75

chamber 214 to cause a rapid movement of the piston 77 toward the left thereby returning the wheel slide base 19 to its initial position. At the same time fluid under pressure also passes through a check valve 218 into the cylinder chamber 208 to cause a rapid movement of the piston 46 toward the right to return the wheel slide 16 to a rearward or inoperative position. It will be readily apparent from the foregoing disclosure that the throttle valves 206, 210, 212, and 216 serve to control the speed of movement of the pistons 46 and 77.

The operation of this improved cam grinding apparatus will be readily apparent from the foregoing disclosure. Assume the valve 154 to be closed to lock the piston 146 in a left-hand end position (Fig. 16) that is with the stop block 148 in an inoperative position. The swivel table 14 is swivelled in a counter-clockwise direction to position the cams No. 1 and No. 2 on the shaft 35 in position relative to the grinding wheel 23. The table is successively indexed longitudinally toward the right to first grind No. 1 and then No. 2 cam. When the table indexes for the No. 3 cam, the dog 197 actuates the limit switch 195 to energize the solenoid S2 thereby shifting the valve member 180 in the control valve 162 into a left-hand end position so that fluid under pressure is passed through the pipe 109 into the cylinder chamber 108 to move the piston 99 upwardly (Fig. 16) thereby swinging the swivel table 14 in a clockwise direction to position cams No. 3 and No. 4 in proper position relative to the grinding wheel 23 so that the grinding wheel 23 has an opposite taper thereon. When the table is indexed to position cam No. 5 in operative relation with the grinding wheel 23, the table dog 199 actuates the limit switch 198 to energize the solenoid S3 thereby shifting the valve member 180 of the control valve 162 into the position illustrated in Fig. 16 so that fluid under pressure passing through the pipe 164 enters the valve chamber 186a, passes through the pipe 186 into the valve chamber 187 in the control valve 161 and through the pipe 106 into the cylinder chamber 107 so as to cause a downward movement of the piston 99 to swing the swivel table 14 in a counter-clockwise direction into the position illustrated in Fig. 16 to position cams No. 5 and No. 6 relative to the grinding wheel 23 so that the peripheral surfaces thereof taper in a direction toward the right. When the table indexes to position cam No. 7 in operative relation with the grinding wheel 23, the dog 196 again actuates the limit switch 195 to energize the solenoid S2 thereby shifting the valve member 180 in the control valve 162 into a left-hand end position so that fluid under pressure causes an upward movement of the piston 99 to swing the swivel table 14 in a clockwise direction so that the cams Nos. 7 and 8 will be ground with a peripheral surface tapering toward the left. After cam No. 8 has been ground, the table 11 traverses through an idle stroke toward the left and returns to its initial position.

If a truing operation is desired after a cam-shaft has been ground, a truing operation may be initiated when the table reaches or approaches its left-hand end position. If a wheel guard truing device is employed then the grinding wheel may be trued at any time during the cycle and if desired the truing operation may be performed automatically. If desired the truing tool 140 may be fixedly mounted on the table 11, in which condition the grinding wheel may be automati-

cally trued as the table approaches a left-hand end position. If desired the truing tool 140 may be mounted on the rock bar 30, as shown in Fig. 16, in which position the valve 154 must be opened so that the gauge block 148 will be moved to an operative position to position the swivel table 14 in a central position during the truing operation. Due to the fact that swivel table 14 is swivelled only a small fraction of one degree, it is not necessary to return the swivel table to a central position unless desired.

The apparatus as illustrated in the drawings is set up so that alternate pairs of cams on a camshaft will be ground with peripheral surfaces tapering in opposite directions and a cam-shaft having eight cams thereon has been illustrated. If desired the apparatus may be set up so that alternate cams will be ground tapering in opposite directions by adding additional table dogs for controlling the limit switches 195 and 198. If desired all of the cams on one end of the camshaft may be ground tapering in one direction while the cams on the other end of the cam-shaft may be ground tapering in the opposite direction by rearrangement of the dogs on the table 11.

It will thus be seen that there has been provided by this invention apparatus in which the various objects hereinabove set forth together with many thoroughly practical advantages are successfully achieved. As many possible embodiments may be made of the above invention and as many changes might be made in the embodiments above set forth, it is to be understood that all matter hereinbefore set forth or shown in the accompanying drawings is to be interpreted as illustrative and not in a limiting sense.

I claim:

1. In a cam grinding machine having a base, a transversely movable wheel head, a rotatable grinding wheel thereon, means to feed said head transversely, a longitudinally movable table, a swivel table thereon, a rotatable camshaft support thereon, means including a motor for intermittently indexing the table longitudinally successively to position a plurality of spaced cams to be ground in operative relation to the grinding wheel, means including an independent motor to swivel said swivel table in either direction, adjustable stops to limit the swivelling movement of the table in either direction, and means actuated by and in timed relation with the longitudinal table movement to control the swivelling means so as to alternately swivel said table in opposite directions after each pair of cams has been grounds to facilitate grinding a predetermined taper in opposite directions on alternate pairs of cams to be ground.

2. In a grinding machine, as claimed in claim 1, in combination with the parts and features therein specified of means to compensate for the swivelling of the swivel table including an indexable member having a plurality of spaced adjustable stops successively to limit the approaching movement of the wheel slide, and means including adjustable dogs on said table to index said member to shift the stop corresponding to the cam being ground into an operative position.

3. In a grinding machine, as claimed in claim 1, in combination with the parts and features therein specified of means for automatically varying the operative position of the wheel head so as to compensate for the swivelling of the swivel table including a rotatable indexable plate, a plurality of spaced stops on said plate to corre-

spond with the spaced portions on the workpiece to be ground, means including a star wheel to rotate said plate, and means including a plurality of adjustable dogs on said table intermittently to actuate said star wheel to index said plate automatically to position the stop corresponding to the cam being ground into an operative position to determine the forward operative position of the wheel head.

4. In a cam grinding machine having a base, a transversely movable wheel head, a rotatable grinding wheel thereon, means to feed said head transversely, a longitudinally movable worktable, a swivel table thereon having a rotatable cam-shaft support thereon, means including a motor for intermittently indexing the table longitudinally successively to position a plurality of spaced cams to be ground in operative relation with the grinding wheel, means including an independent motor to swivel said swivel table in either direction, adjustable stops to limit the swivelling movement of the swivel table in either direction, and means automatically actuated by and in timed relation with the longitudinal movement of the table to control the swivel means so as to swivel the swivel table in one direction to facilitate grinding a predetermined taper in one direction on a portion of the cams to be ground and to swivel said swivel table in the opposite direction to facilitate grinding a predetermined taper in the opposite direction on the remainder of the cams to be ground.

5. In a grinding machine having a base, a transversely movable wheel head having a rotatable grinding wheel thereon, a longitudinally movable table, a swivel table thereon having a rotatable work support thereon, means for moving the table longitudinally to position a workpiece relative to the grinding wheel, means to swivel said swivel table in either direction to facilitate grinding tapers in opposite directions on spaced portions of the workpiece, means including an index pawl to facilitate locating the swivel table in a central position for a truing operation, and means actuated by and in timed relation with the longitudinal movement of the table to control the movement of said pawl.

6. In a grinding machine having a transversely movable wheel head, a rotatable grinding wheel thereon, for the head, means to feed said head transversely, a longitudinally movable worktable, a swivel table thereon having a rotatable work support, means for moving the table longitudinally successively to position spaced portions of a workpiece relative to the grinding wheel, a fluid motor to swivel said swivel table in either direction, and means including a control valve mechanism actuated by and in timed relation with said table movement to control the swivel motor so as to swivel said swivel table in one direction to facilitate grinding a predetermined taper in one direction on part of the portions to be ground, and to swivel said swivel table in the opposite direction to facilitate grinding a predetermined taper in the opposite direction on the remainder of the portions to be ground.

7. In a cam grinding machine having a base, a transversely movable wheel head, a rotatable grinding wheel thereon, means to feed said head transversely, a longitudinally movable table, a swivel table thereon having a rotatable camshaft support, means for moving the table longitudinally successively to position spaced cams in operative relation to the grinding wheel, a piston and cylinder to swivel said swivel table in either

direction, adjustable stops to limit the swivelling movement of the swivel table in either direction, and means including a control valve mechanism actuated by and in timed relation with the table movement to control the piston and cylinder so as to alternately swivel said swivel table in opposite directions after each cam has been ground to facilitate grinding a predetermined taper in opposite directions on alternate cams to be ground.

8. In a cam grinding machine having a base, a transversely movable wheel head, a rotatable grinding wheel thereon, a means to feed said head transversely, a longitudinally movable table, a swivel table thereon having a rotatable camshaft support, means for moving the table longitudinally successively to position spaced cams in operative relation to the grinding wheel, a piston and cylinder to swivel said swivel table in either direction, adjustable stops to limit the swivelling movement of the swivel table in either direction, and means including a control valve mechanism actuated by and in timed relation with the table movement to control the piston and cylinder so as to alternately swivel said swivel table in opposite 25 directions after each pair of cams has been ground to facilitate grinding a predetermined taper in opposite directions on alternate pairs of cams to be ground.

9. In a cam grinding machine having a base, a transversely movable wheel head, a rotatable grinding wheel thereon, means to feed said head transversely, a longitudinally movable worktable, a swivel table thereon having a rotatable cam-shaft support thereon, means for moving the table longitudinally successively to position successive cams in operative relation with the grinding wheel, a fluid motor to swivel said swivel table in either direction, adjustable stops to limit the swivelling movement of the swivel table in either direction, and means including a control valve mechanism automatically actuated by and in timed relation with the longitudinal movement of the table to control the swivel motor so as to swivel the swivel table in one direction to facilitate grinding a predetermined taper in one direction on a portion of the cams to be ground and to swivel said swivel table in the opposite direction to facilitate grinding a predetermined taper in the opposite direction on the remainder of the cams to be ground.

10. In a grinding machine having a base, a transversely movable wheel head having a rotatable grinding wheel thereon, a longitudinally movable table, a swivel table thereon having a rotatable work support thereon, means for moving the table longitudinally to position a workpiece relative to the grinding wheel, a fluid motor to swivel said swivel table in either direction to facilitate grinding tapers in opposite directions on spaced portions of the workpiece, means including an index pawl to facilitate locating the swivel table in a central position for a truing operation, and means including a piston and cylinder actuated by and in timed relation with the longitudinal movement of the table to control the movement of said pawl.

11. In a grinding machine having a base, a transversely movable wheel head, a rotatable grinding wheel thereon, means to feed said head transversely, a longitudinally movable worktable, a swivel table thereon having a rotatable work support thereon, means for moving the table longitudinally successively to position spaced portions on a workpiece relative to the grinding 75

wheel, a fluid motor to swivel said swivel table in either direction, adjustable stops to limit the swivelling movement of the swivel table in either direction, means including a solenoid-actuated control valve for controlling said swivel motor, a plurality of table dogs adjustably mounted on said table, and means including a switch actuated thereby for controlling said valve automatically to swivel said swivel table in timed relation with the table movement.

12. In a grinding machine having a base, a transversely movable wheel head, a rotatable grinding wheel thereon, means to feed said head transversely, a longitudinally movable worktable, a swivel table thereon having a rotatable work support thereon, means for moving the table longitudinally successively to position spaced portions on a workpiece relative to the grinding wheel, a fluid motor to swivel said swivel table in either direction for a taper grinding operation, adjustable stops to limit the swivelling movement of the swivel table in either direction, means including a solenoid-actuated control valve for controlling the fluid motor, means including an index pawl to facilitate locating the swivel table in a central position for a truing operation, a fluid motor to actuate said pawl, means including a solenoid-actuated control valve therefor, a plurality of adjustable dogs on said table, and a plurality of limit switches actuated by said dogs to actuate the control valves in timed relation with the longitudinal movement of said table.

13. In a cam grinding machine having a base, a transversely movable wheel head, a rotatable grinding wheel thereon, means to feed said head transversely, a longitudinally movable table on said base, a swivel table thereon, a rock bar pivotally supported on said swivel table, a rotatable camshaft support on said rock bar, means including a plurality of master cams and a follower roller in engagement therewith interposed between the rotatable work support and the table to impart a rocking movement to said bar to facilitate grinding predetermined contours on a plurality of spaced cams on a cam shaft to be ground, means including a motor for indexing said table longitudinally successively to position a plurality of spaced cams to be ground in operative position relative to the grinding wheel, and means including an independent motor to swivel said swivel table in either direction, adjustable stops to limit the swivelling movement of the table in either direction and means actuated by and in timed relation with the longitudinal movement of the table to control the swiveling motor so as to alternately swivel said table in opposite directions after each pair of cams has been ground to facilitate grinding a predetermined taper in opposite directions on alternate pairs of cams to be ground.
